UNITED STATES PATENT OFFICE.

ERICH JUNGE, OF STATEN ISLAND, NEW YORK.

INTERNAL-COMBUSTION ENGINE.

Application filed February 18, 1925. Serial No. 9,935.

The present invention relates to an internal combustion engine and has to do particularly with a novel form of engine of greater simplicity, less weight, and more 5 flexibility than internal combustion engines now in common use for furnishing motive power.

Heretofore diminution of engine bulk and weight has been sought to be accomplished 10 by multiplying the number of cylinders working on one and the same crank shaft. Thus the V-type engine, the radial engine and also the rotary engine were developed effecting considerable savings in point of 15 weight but failing to eliminate and even augmenting the complications which result from the employment of separate cylinders with their valve gears, inlet and exhaust piping, cam shafts and other accessories.

20 The principle underlying the following invention purports to accomplish an even greater saving in bulk and weight and in addition to eliminate all complicated and ineffective machine parts mentioned above by 25 combining four or more cylinders in such a way that their crank and combustion chambers form one continuous annular casing in which the various pistons work in synchronism on two or more separate cranks.

30 This new combination incorporates a number of advantages over the usual type of engine among which may be mentioned the fact that the weight of the engine per unit of power output is reduced to about 35 one fourth of that ordinarily obtained in engines such as those commonly used in the automotive industry, the manufacturing cost of an engine of given power output is about one third that of the ordinary engine and 40 the fuel consumption per ton-mile is about one half that obtained with the ordinary four stroke cycle automobile engines at present in common use.

A preferred embodiment of the invention 45 is illustrated in the accompanying drawings in which Figure 1 is a transverse sectional view of an internal combustion engine embodying my invention and Figure 2 is a similar view showing a modified construction.

50 The illustration of Figure 1 is somewhat diagrammatic in character and serves primarily to indicate the relation of the various pistons, the location of the ports and gas 55 passages with respect to the pistons and cylinders and the general structural arrange-

ment of the various parts of the engine. As may be seen from Figure 1, the engine consists essentially of the combination of two V motor units, the respective V units in the 60 drawing being on opposite sides of the central vertical axis of the engine. The two motor units are so constituted as to employ common combustion chambers 1 and 2 here shown respectively at the top and bottom of 65 the engine. These combustion chambers may be connected by means of a pipe 3 having in it a control valve 4 if desired so that pressure conditions within the respective combustion chambers may be equalized. 70

The V motor unit at the left side of the engine shown in Figure 1 consists of pistons 5 and 6 operating by means of the ordinary connecting rod attachment with the crank shaft 9. The cylinders in which the 75 pistons operate are here shown at an angle of about 120° with each other. The other V motor unit which occurs at the right hand side comprises pistons 7 and 8 operating in their respective cylinders and driving the 80 crank shaft 10 through the medium of suitable connecting rods. The two crank shafts 9 and 10 are connected together by means of a link or driving rod 11 to insure synchronous operation of the respective shafts, but 85 they can also be connected by means of gear wheels acting on a central shaft. Since the engine pistons are associated in fixed angular relation with their respective crank shafts and the shafts are connected by means 90 of the link 11, the pistons are at all times caused to operate in perfect synchronism, though one set may precede the other. The arrangement shown is such that the two upper pistons 6 and 7 descend at the same 95 time and during this time the lower pistons 5 and 8 ascend simultaneously so that the positions of the respective pistons at the commencement of their compression strokes is as indicated in Figure 1. With this ar- 100 rangeement, all of the pistons operate on their compression stroke at the same time, the explosions in the respective combustion chambers 1 and 2 occur at the same time and the power strokes of the various pistons take 105 place at the same time.

As will be seen from the drawing, the respective engine cylinders are arranged about the central portion containing the air ports. These various cylinders constitute a 110 continuous chamber of approximately annular form surrounding the central structure of

the engine. The ports arranged in this central portion serve to establish the requisite communication between the respective cylinders. The port 13 serves as an air inlet for the cylinders occupied by pistons 5 and 6 while the opening 14 serves as the air inlet for the other two cylinders. This air is passed through ports 17 and 18 into the cylinders as soon as the pistons uncover these ports at substantially the lower extremity of their strokes. Fuel is injected by means of a separate pump or blower through ports 19 or 20 or both, while exhaust gases escape through the ports 21 and 22. Ignition is effected by means of spark plugs 23 and 24 extending into the combustion chambers 1 and 2 at the proper point, unless the Diesel principle is employed. The entire engine which consists essentially of two V motor units combined in the fashion above described operates on the one cycle principle, giving two impulses for every revolution.

During operation of the engine, air enters through the openings 13 and 14 during the compression strokes of the respective pistons. This air enters the crank case and is compressed during the power stroke of the pistons, valves being provided at the openings 13 and 14 to prevent the escape of the air drawn in during the compression stroke. As the power stroke of the pistons proceeds, the pistons 5 and 6 draw together into the position shown in the drawings and uncover the inlet ports 17 and 18 which through ducts 15 and 16 communicate with the respective crank case housings. When the ports 17 and 18 are uncovered, a rush of air occurs from the crank shaft housings into the respective combustion chambers 1 and 2 after the fashion indicated by the arrows. This air replaces the spent gases which are exhausted from the engine through the exhaust ports 21 and 22. The exhausting of the gases occurs approximately during the same time interval that the fresh incoming air is admitted through ports 17 and 18, and this rush of air therefore serves both as scavenging air and as air available for combustion during the next power stroke of the pistons.

Immediately following the entrance of the air through the ports 17 and 18, the fuel mixture is injected through the fuel inlets 19 and 20 which open slightly later than the air ports 17 and 18, thus the incoming fuel charge which, of course, is varied according to the load on the motor always meets the air necessary for combustion and is intermixed with it in the combustion chamber. The mixture of fuel and air is subjected to requisite pressure during the compression stroke of the pistons and ignition is effected at the termination of the compression stroke through the medium of the spark plugs 23 and 24. In case the equalizing

line 3 is employed, the pressure in the two chambers is balanced by a flow through this line should any inequalities in pressure occur, as for instance, if more fuel was admitted to the upper group of cylinders than to the lower.

Besides attaining the utmost reduction of bulk and weight compatible with simplicity and cheapness of construction, as well as reliability and economy of operation and perfect balance, this invention purports to raise the flexibility of internal combustion motors to the level of the steam engine. This feature is realized by connecting the two opposite combustion chambers in Figure 1 by means of an air pipe 3, thus constituting practically a common combustion chamber when valve 4 is open.

If fuel is injected into one chamber only, combustion will be confined to said one chamber, but expansion will be transmitted by means of said pipe and the compressed medium of charge contained therein, to the other chamber or chambers, thus acting on all four or more pistons at the same time.

Hence, instead of expanding the charge only to the limit of the stroke volume defined by the down stroke of the two pistons of one chamber, the power charge in this motor can expand, if desired, to the limit of the total stroke or piston displacement volume of all four or more pistons, acting in synchronism. Thus a high initial but a low final pressure is attained and the potential heat value of the charge is utilized to the full extent.

If higher loads are to be carried, fuel is injected not only into one but also into the other combustion spaces, whereby a double or greater quantity of charge can be burned at the same compression pressure, and the output of the motor can be augmented accordingly. Perfect balance of all primary and secondary forces is attained in this system at all loads, because expansion acts on all pistons simultaneously, and all angular and opposing forces absorb each other.

This double or triple expansion by stages superimposed upon each other is essentially different from compounding with the stages following one another as heretofore practiced. To properly designate this unique action and to distinguish it from conventional types this motor, giving two impulses for every revolution of the crank shaft or shafts, may be termed the One cycle motor.

Owing to its symmetric form, compactness, light weight and perfect balance, the motor of this application is especially adapted for aircraft work, propulsion of high speed boats and the like. The shape and design of the motor render it particularly adaptable for incorporation into bodies or hulls which are to be fashioned in stream line design.

An important feature of the present motor

is the fact that it embodies means for increasing (for instance doubling of the motor shown in Figure 1) the output over the normal load capacity of the motor. This feature 5 renders the motor particularly valuable for transportation uses either by air, land or water and at once provides an ample reserve of power which is available for handling peak loads such as are encountered for instance in hill climbing and the like.

While an engine consisting of two V motor units as shown in Figure 1 is probably the most practical engine from the standpoint of construction and design, the principle 15 of operation of the apparatus may be carried out in a motor consisting of a greater number of units, for instance, three units as shown in Figure 2. In the engine of Figure 2, three pairs of pistons 28, 29 and 30 20 are arranged about the central portion and operate in conjunction with common combustion chambers 25, 26 and 27. A single enclosing housing 31 is provided to constitute the body structure of the engine and 25 partitions 32 and 33 are provided at the inner sides of the various groups of pistons to thus constitute the passages for the incoming air. During operation of the engine air is drawn in by each pair of pistons as 30 for instance through the opening 34 and is compressed in the crank case during the down stroke of the pistons. When the pistons have reached the positions shown in Figure 2, the compressed air in the crank 35 case passes through the port 35 into the air passage formed by partitions 32 and 33 from whence it enters combustion space 25 through the port 36. The in-rush of fresh air through port 36 serves to scavenge the 40 combustion chamber and the spent gases exhausted through port 38. Fuel is injected through opening 37 at substantially the same time that the fresh air charge enters through port 36. Compression of the air 45 and charge in the combustion chamber follows and ignition is effected in the ordinary manner. A similar action takes place in each of the combustion chambers 25, 26 and 27.

50 Certain changes in structure and arrangement may be made in the engine within the scope of the appended claims. The present invention contemplates an engine of greatly reduced bulk and weight, reduced manufacturing cost, and greater flexibility as compared with the ordinary type of internal combustion engines now employed in automobile and aircraft work. It will be noted that with the structural arrangement employed, a perfect balancing of the moving parts of the engine is secured.

I claim:

1. An internal combustion motor compris-

ing a plurality of pairs of cylinders set at an angle one to the other, a piston working 65 in each of said cylinders, a common crank shaft for the pistons of each pair of cylinders, a combustion chamber between one piston of one pair and the adjacent piston of the adjacent pair, intake and exhaust ports 70 for said combustion chamber, said ports arranged to be opened and closed by the movement of the pistons, a similar chamber between other adjacent pistons and a connection between the combustion chamber and 75 said last mentioned chamber for transmitting the pressure in the combustion chamber thereto.

2. An internal combustion motor comprising a plurality of pairs of cylinders set at 80 an angle one to the other, a piston working in each of said cylinders, a common crank shaft for the pistons of each pair of cylinders, a combustion chamber between one piston of one pair and the adjacent piston of 85 the adjacent pair, a compression chamber formed by the pistons of one pair of cylinders, intake and exhaust ports for said combustion chamber, said ports arranged to be opened and closed by the movement of the 90 pistons, and passages from said compression chamber to said intake port.

3. An internal combustion motor comprising a plurality of cylinders set at an angle 95 one to the other, a piston working in each of said cylinders, a common crank shaft for the pistons of each pair of cylinders, a combustion chamber between one piston of one pair and the adjacent piston of the adjacent pair, inlet ports at one end, respectively, of 100 said combustion chamber, exhaust ports at the other end thereof, said ports being arranged to be opened and closed by the movement of said pistons, a compression chamber formed by the pistons of one pair of cylinders and a passage leading from said compression chamber to said inlet port. 105

4. An internal combustion motor comprising a plurality of cylinders set at an angle one to the other in substantially annular arrangement, a piston working in each of said cylinders, a common crank shaft for the piston of each pair of cylinders, combustion chambers between one piston of each pair and the adjacent piston of the adjacent pair, 115 separate fuel and air inlet ports at one end, respectively, of each of said combustion chambers, exhaust ports at the other ends thereof, said ports being arranged to open and close by the movement of said pistons, compression chambers formed by the piston of each pair, and passages from said compression chambers to the air inlet ports of 120 said combustion chambers.

In testimony whereof I affix my signature.
